UNITED STATES PATENT OFFICE.

MABEL R. BISHOP AND FRANKLIN L. BISHOP, OF CLEVELAND, OHIO.

COLLAPSIBLE TUBE.

Application filed September 28, 1925. Serial No. 59,085.

Our invention relates to collapsible tubes and means which may be used therewith to eject the contents of the tube cleanly and neatly at intervals whenever desired. Thus, 5 our aim is to provide a simple device for holding and squeezing a collapsible tube containing paste, cream, etc., and also to provide a delivery nipple which may be readily attached to the discharge mouth of the tube 10 and which will be self-acting to cut off the supply cleanly and to seal the mouth of the tube against the admission of air at the close of each collapsing operation.

In the accompanying drawings, Fig. 1 is 15 a top view of our improved squeezing device for a collapsible tube and Fig. 2 is a sectional view of said device together with a collapsible tube held therein and provided with our improved self-sealing delivery nipple. Fig. 20 3 is a perspective view of a collapsible tube corresponding to the tubes sold generally with a removable screw cap. Fig. 4 is a perspective view of a rubber nipple which may be substituted for the screw cap, and 25 Figs. 5 and 6, are sectional views in different planes actually through said rubber nipple. Fig. 7 is a sectional view of a spring contracted band which may be used with the rubber nipple. Fig. 8 is a perspective view 30 of same rubber nipple with a split spring ring sleeved thereon.

As shown, the collapsible tube T shown in the drawings exemplifies the common form 35 of tube in general use having collapsible walls, a flattened end portion 2, and a screw-threaded extension or neck 3 of reduced diameter through which the contents of the tube is discharged, providing the screw cap (not shown) is removed. We substitute for 40 this screw cap a rubber nipple N having a counterbored central opening 4 which communicates with a cross slit 5 extending through the top of the nipple. Preferably, slit 5 is merely a knife-cut to permit close 45 contact of the opposing faces where severed so that when the contents of the tube is forced through central opening 4 the severed portions of the tube will be pressed apart to permit the material to escape in the form of 50 a thin, flat strip. The upper and larger portion of central opening 4 is of smaller diameter than the screw-threaded extension 3 of tube T so that the nipple may be firmly connected or fastened to the extension, and further, so that the upper part of the nipple 55 will be expanded in substantial degree with

drawing effect on the tip portion having slit 5. In other words, in attaching the nipple the spreading of the upper half of the nipple having annular bead 6 causes the severed sides of the tip part of the nipple to press more tightly together, thereby closing the slit tightly and sealing the entrance to opening 4 more effectively by reason of said attachment. The top portion of the nipple 60 may be tapered or ribbed and grooved angularly as shown to further foster the self-closing and self-sealing effect, and in addition a spring metal band 7 may be sleeved around the upper end of the nipple, and this 65 band may be provided with spring tongues 8 adapted to overlap and press inwardly against the top portion of the nipple at each side of slit 5, thereby supplementing the inherent tension produced in the top portion 70 when the nipple is sleeved over extension 3. In Fig. 8 we show a split wire ring 9 sleeved over the slotted top portion of nipple N in lieu of a band 7 having tongues 8, the split 75 ring being made of spring material to permit the severed sections to yield and spread apart under pressure from within. It should also be understood that the elasticity of the rubber will permit the material passing through the nipple to crowd slit 5 open, and that 80 when spring tongue 8, or a split ring 9, is used a greater restraint is placed on the passage of the material through the nipple, and that when the pressure on the tube is relieved 85 and stopped the split portion of the rubber 90 nipple will close slit 5 tightly and cut-off the flow of the material therethrough and also seal the entrance against admission of air, thereby preventing the hardening of certain 95 kinds of materials which are dispensed in such tubes.

A nipple N such as described may be attached to and used with any collapsible tube containing dental paste, shaving cream, or any other similar plastic composition, and 100 these tubes may be collapsed by hand as ordinarily practiced. However, such nipples are especially desirable and useful on collapsible tubes when placed within a power 105 squeezing device, for example, a device such as shown in Figs. 1 and 2 of the drawings, comprising a pair of rubber rollers 10 and 11, which are mounted on parallel shafts 12 and 13, journaled in an angular frame 14 having 110 a supporting bracket 15. The shafts are provided with meshing gears 16 and 17 at one side of the frame, and a thumb piece 18

is affixed to one of the shafts to permit its rotation by hand. The flattened end 2 of a tube T may be inserted between the rollers, and fed upwardly by turning the handwheel, thereby squeezing the contents of the tube through the mouth thereof and nipple end, and the nipple will function effectively as described.

What we claim is:

- 10 1. An attachment nipple, for a collapsible tube having a screw-threaded extension with a central discharge opening, comprising a relatively short cylindrical body made of rubber having a circular opening at one end normally of less diameter than the tube extension and formed with a slit at the opposite end connected to said circular opening by a short bore of lesser diameter than the discharge opening for said tube, the wall surrounding said short and small bore being relatively thicker than the wall surrounding the said opening, whereby the slotted sides of the nipple are forcibly pressed together when the nipple is expanded and connected to the tube extension.
- 15
- 20
- 25

2. A rubber attachment nipple for a collapsible tube having a nozzle with a central discharge opening, said nipple having a slotted tip and a bore adapted to connect the slit with the central discharge opening in 30 said nozzle, in combination with resilient clamping means adapted to constantly press the slotted sides of the tip together, except when pressure is applied to the tube sufficient to overcome the opposing pressure of 35 said clamping means.

3. A rubber delivery nipple for collapsible tubes, having a discharge opening, and resilient clamping means sleeved upon said nipple adapted normally to close said opening when pressure is removed from the tube. 40

4. A rubber attachment nipple for collapsible tubes, having an expansible connecting portion and a slotted tip portion, and a spring member encircling said nipple. 45

In testimony whereof we affix our signatures.
